(57) **CLAIM**

The ornamental design for a metal molding machine, as shown and described.

DESCRIPTION

FIG. 1 is a perspective view of a metal molding machine;

FIG. 2 is a front elevational view thereof;

FIG. 3 is a rear elevational view thereof;

FIG. 4 is a top plan view thereof, the opposite side view omitted for its heavy weight;

FIG. 5 is a left side elevational view thereof; and,

FIG. 6 is a right side elevational view thereof.

The broken line showing is for illustrative purposes only and forms no part of the claimed design.
